UNITED STATES PATENT OFFICE.

MICHEL BUIVID, OF WHITESTONE, NEW YORK.

DESIGN FOR A BADGE OR SIMILAR ARTICLE.

Application filed June 11, 1927. Serial No. 22,393. Term of patent 3½ years.

To all whom it may concern:

Be it known that I, MICHEL BUIVID, a subject of Russia, residing at Whitestone, in the county of Queens and State of New York, have invented a new, original, and ornamental Design for Badge or Similar Article, reference being had to the accompanying drawing, forming part thereof.

Fig. 1 is a face view of an ornamental badge or similar article, showing my new design.

Fig. 2 is an edge view of the same.

I claim:

The ornamental design for a badge or similar article, as shown.

In testimony whereof I have affixed my signature.

MICHEL BUIVID.
